REGULATOR

Bascom O. Austin, Lima, Ohio, assignor to Westinghouse Electric Corporation, East Pittsburgh, Pa., a corporation of Pennsylvania

Application January 12, 1944, Serial No. 517,918

3 Claims. (Cl. 201—51)

This invention relates to electrical apparatus and, in particular, to regulators of the pile type.

An object of this invention is to provide a lightweight regulator of the pile type which is stable in operation and is provided with a stationary pressure plate capable of being externally adjusted.

Another object of the invention is to provide in a sealed pile regulator for externally making adjustments in the setting of a stationary pressure plate within the sealed casing of the regulator.

Other objects of this invention will become apparent from the following description when taken in conjunction with the accompanying drawing, the single figure of which is a view in elevation and partly in section of a regulator embodying the teachings of this invention.

Referring to the drawing, this invention is illustrated by reference to the regulator 10 shown therein. The regulator 10 is of the pile type having a stack 12 of aligned disks 14 of high resistance material such as carbon or the like mounted in a sectionalized housing or casing 16 and disposed to be operated by an electromagnet 18. The casing 16 is formed of a plurality of sections, and end or base section 20 being connected to an opposite end section 22 by an intermediate constricted section 24.

The stack 12 of disks 14 of high resistance material, is assembled in operative relation on a shaft or rod 26 of insulating material such as a ceramic rod, the rod 26 extending through openings 28 positioned centrally in each of the disks 14 for maintaining the disks in aligned relation. One end of the rod 26 is supported in a sleeve 30 of conducting material, the sleeve 30 being secured to a ring 32 of conducting material as by means of the flared ends 34 and the shoulder 36 carried at one end of the sleeve for forming a recess into which the ring 32 is fitted. The ring 32 is, in turn, secured to the face of a plug 38 which is disposed centrally of a diaphragm 35 which is positioned with its periphery seating against the shoulder 37 carried by the end section 22. The ring 32 is secured to the face of the plug 38 by means of the screws 38 disposed in spaced relation about the sleeve 30, the screws 38 being insulated from the ring 32 of conducting material by means of the insulating bushings 40 and washers 42. The ring 32 is also insulated from the face of the plug 38 by means of a sheet 44 of insulating material, such as fish paper or the like, which is disposed over the face of the plug 38.

As illustrated, the end of the plug 38 opposite the face to which the ring 32 is mounted is provided with a centrally located threaded recess 43, the purpose of which will be explained more fully hereinafter. The plug 38 is sealed to the diaphragm 35 by applying solder 45 to the joint formed where the end of the plug 38 projects through the diaphragm 35. Similarly the diaphragm 35 is sealed in its assembled position with its periphery seating against the shoulder 37 by applying solder 47 or the like to the periphery of the diaphragm and the end cap 22. The diaphragm thus functions to seal the end of the end section 22.

15 In order to provide an electrical connection external of the housing or casing 16, the ring 32 of conducting material carries a projection 48 for receiving a screw 49 which is utilized for connecting one end of a conductor 50 to the ring, the other end of the conductor being secured to a conducting bolt 52 which extends through the side wall of the end section 22, insulating washers 54 and an insulating bushing 56 being provided for insulating the bolt 52 from the end section 22. As illustrated, a pressure plate 58 is disposed between the other flanged end of the conducting sleeve 30 and the end of the stack 12 of disks 14 for distributing pressure over the face of the stack, the pressure plate 58 preferably being sealed to the sleeve 30 to provide a good electrical connection therebetween.

20 The other end of the rod 26 projects from the other end of the stack 12, a pressure plate 60 being disposed about the shaft 26 adjacent the end of the stack 12. The pressure plate 60 is secured to a sleeve 62 positioned about the rod 26 in a manner similar to the mounting of the pressure plate 58. The sleeve 62 is similar to the sleeve 30, being provided with a shoulder 64 and a flared outer end 66 spaced therefrom for holding a ring 68 of conducting material. The ring 68 is similar to the ring 32 at the opposite end of the stack, having a projection 70 for receiving a screw 72 for securing one end of a conductor 74 thereto. The other end of the conductor 74 is secured to the bolt 52 which projects through but is insulated from the section 20 of the casing in a manner similar to the mounting of the bolt 52.

25 As illustrated, the section 20 of the housing or casing 16 has an inwardly projecting partition 78 disposed about its periphery approximately midway of the length of the section. On one side of the partition 78, a ring 80 of stainless steel or the like having a sloping or beveled surface 82 is dis-

posed to seat against the outer walls of the section 20 and the partition 78. The ring 80 is of such a size that an armature member 84 may be fitted within the inner diameter of the ring.

The armature member 84 utilized in the regulator 10 is substantially a disk and is carried by the ring 80 which is secured to the sleeve 104. The armature member 84 is preferably faced on one side thereof by a sheet or layer of insulating material 86 which functions to electrically separate the armature member 84 and a spring member 88. The spring member 88 illustrated is a leaf spring and may be of star-shape or may be a circular disk, the ends or outer periphery of which are bent to seat against the sloped surface 82 of the ring 80, the purpose of which will be more fully described hereinafter. In order to hold the spring 88 in the position described, a reinforcing sheet 90 of metal or the like is placed adjacent the surface of the spring 88 opposite the surface in contact with the sheet 86 of insulating material, and a layer 92 of insulating material is then placed against the supporting sheet 90. This assembly of the insulating sheet 92, reinforcing plate 90, spring member 88, insulation 86, and the armature member 84 is held together as an integral unit by means of the screw 94 and is mounted as an integral unit on the ring 80 by means of the screw 96, the screw 96 being insulated from the ring 80.

As illustrated, a winding 98 having leads 97 and 99 is positioned on the other side of the partition 78 of the section 20 and disposed to be encased in the housing 16. However, before the winding 98 is positioned in the casing 16, a ring 100 of brass or similar nonmagnetic material is secured about the inner circumference of the ring 78 as by brazing, as shown at 102, and a metallic sleeve 104 provided with threads on its inner surface is secured to the inner circumference of the brass ring 100 as by brazing at 106, as illustrated. In positioning the winding 98 in the housing, the winding preferably mounted on a spool 108 of insulating material is slipped over the end of the sleeve 104 to a position where the side wall of the insulating spool 108 seats against the partition 78, and the brass ring 100 and the leads 97 and 99 project through suitable openings in the casing. In this position, an end cap or plate 110 may be secured to the ends of the section 20 of the housing by the bolts 112 which are disposed in spaced relation about the periphery of the end plate 110. The end plate 110 seating against the winding 98 maintains the winding in position about the sleeve 104 and prevents a movement of the winding.

With the winding 98 assembled as described, a core member 114 having an externally threaded surface is threaded into the threaded sleeve 104 to a position where the end of the core member 114 is spaced a predetermined distance from the armature member 84. By adjusting the position of the core member 114, a predetermined position of the core member may be obtained where a required balance between the magnetic pull and the force of the spring member 88 is obtained over an operating range of the regulator. This position of the core member 114 will necessarily depend upon the strength of the spring member 88 which is positioned to apply pressure to the stack 12 and the slope of the sloped surface 82 of the ring member 80, it being noted that as the armature member is moved under the influence of the magnetic pull, that the effective arm length of the spring member 88 changes

more and more of the spring 88 engages the sloped surface 82 of the ring 80. When the core member 114 is thus adjusted to obtain the required gap between the armature member and the core member, the external end of the sleeve 104 and the core 114 is brazed as at 118 for sealing the threaded joint between the two members. The threaded joints between the end cap 22 and the constricted section 24 is likewise brazed as at 118, and the threaded joint between the constricted section 24 and the end section 20 of the casing is also brazed as at 120 to provide a sealed casing about the movable elements of the regulator 10.

As will be noted, the constricted section 24 of the casing is of a size determined by the size of the stack 12 utilized in the regulator. Preferably the constricted length of the section 24 has a diameter only slightly greater than that of the stack of disks, spacing being provided, however, for the position of a sleeve 122 of insulating material such as porcelain, the sleeve being spaced slightly from the stack 12. As illustrated, the sleeve 122 of porcelain is maintained in position by brazing ring members 124 and 126 to the constricted section 24 at opposite ends of the sleeve 122. The ring members 124 and 126 effectively prevent longitudinal movement of the sleeve 122.

In order to effectively aid in dissipating any heat that may be generated in the stack 12 of disks 14, a plurality of radiating fins 128 are disposed about the constricted section 24 of the casing, the fins 128 being preferably formed of aluminum or the like and being formed on a sleeve 130 which fits about the constricted area. The sleeve and fin assembly may be formed in two half sections which when placed about the constricted section 24 may be bolted together to form a continuous radiating assembly about the constricted section 24.

As illustrated, the end cap 22 is also provided with a vent 132 which may be sealed. After the regulator is assembled, the housing or casing 16 is preferably evacuated, suitable vacuum equipment, not shown, being attached to the vent 132 for accomplishing this purpose, and when evacuated, a thermally conducting electrically insulating fluid medium 134 is admitted to the housing. The fluid medium 134 may be either gaseous or liquid, the main requirement being that the medium utilized be inert to the material, such as carbon, which is utilized in forming the disks 14 of the stack, and that it has no chemical effect on the composition of the other movable elements within the casing.

The gases helium and hydrogen are especially suited for use in the casing 16 as they are inert with respect to the disks, making it possible to operate the regulator at elevated temperatures without destroying the disks 14. Further, hydrogen and helium transmit heat at a rate about six times faster than can be obtained if the thermally conducting fluid medium is not present within the casing. As the gases are inert with respect to the disks of resistance material, a longer life of the disks can be obtained as the gas prevents frosting or freezing of the disks due to sweating and also prevents deterioration of the disks by excluding oxygen therefrom.

Where a liquid medium is used instead of the inert gaseous medium, it is preferred to employ a permanently liquid dialkyl silicone. Of the known silicones, that silicone liquid which is essentially dimethyl silicone which has been poly-

merized and is free of mono-methyl silicone groups is preferred. The essentially dimethyl silicones are produced by fractionating a mixture of methyl silicone ethoxides to separate the dimethyl silicone diethoxide as a substantially pure component which is hydrolyzed to the dimethyl silanol and then dehydrated with an agent such as sulphuric acid to dimethyl silicones of predetermined molecular size. By fractionating the oily dimethyl silicones, a stable liquid of predetermined viscosity may be obtained. This process and product are described in greater detail in the copending application of J. G. Ford and J. R. Wenzel, Serial No. 439,066, filed April 15, 1942, and assigned to the assignee of this invention. The dimethyl silicone insulating medium is especially suited for use in the regulator of this invention, as it is especially stable over wide ranges of temperature, very little change in viscosity being encountered over ranges of from 20 -70° F. up to as high as 500° F.

After the fluid medium 134 is admitted to the housing 16, a cap 136 is placed upon the vent 132 and the joint is brazed or soldered as at 138 for effectively sealing the vent. Thus, all the moving elements of the regulator are enveloped in a fluid insulating medium, and the casing is sealed to prevent loss or contamination of the fluid insulating medium.

As illustrated, the end section 22 has side walls which project beyond the diaphragm 35, the side walls being threaded as at 140. An end cap 142, the sides of which are threaded as at 144 is disposed in threaded engagement with the threaded end 140 of the end section 22. Centrally disposed of the end cap 142 is an inwardly projecting plug 146 threaded as at 148 for cooperating with the threaded recess 43 of the plug 33.

As illustrated, the threaded plug 146 is disposed in threaded engagement with the threaded recess 43 as the end cap 142 is threaded on the end section 22. Thus, as the end cap 142 is screwed onto the section 22, the threaded engagement of the plug 146 with the plug 33 carried by the diaphragm 35 effects a movement of the diaphragm and, consequently, a movement of the pressure plate 58 to a predetermined setting, the pressure plate 58 being normally considered as stationary. In order to control the fineness of the adjustment of the position of the diaphragm, to adjust the setting of the pressure plate 58 within the sealed casing, the pitch of the threads 144 and 148 and, consequently, the pitch of the threads 140 and those of the threaded recess 43 are controlled in a definite manner. For example, if the threads 144 on the cap 142 are 32 per inch, and the threads 148 on the plug 146 are 40 per inch, then one complete turn of the end cap 142 will move the diaphragm 35 or the pressure plate 58 a distance of .00625 inch. Since the movement of the pressure plate 58 is the differential between the pitches of the threads carried by the end cap 142 and the plug 146, it is apparent that the fineness of the adjustment can be controlled by making the pitch of the two threads approach one another. By utilizing the differential of the threads, it is possible with the assembly described hereinbefore to make adjustments in the setting of the pressure plate 58 within the sealed casing in fractions of one-thousandths of an inch, giving a sensitive adjustment for the regulator.

The regulator of this invention is very efficient, it being apparent that the fluid insulating medium 134 effectively dissipates heat generated in the stack 12 of disks 14, the fluid medium provid-

ing a continuous thermally conducting path from the disks to the radiating fins 128 carried about the constricted section 24. Further, the fluid insulating medium functions to suppress arcing between the disks of resistance material, thereby preventing deterioration of the disks and greatly prolonging the life of the regulator. In addition to the efficient dissipation of heat and the prevention of deterioration of the elements, the mechanism for adjusting the setting of the stationary pressure plate 58 renders the regulator efficient for installation, it being apparent that very fine adjustments of the regulator can be readily accomplished.

Although this invention has been described with reference to a particular embodiment thereof, it is, of course, not to be limited thereto except insofar as is necessitated by the scope of the appended claims.

I claim as my invention:

1. In a sealed regulator, in combination, a stack of disks of resistance material, a pressure plate at each end of the stack of disks, a spring member disposed to apply pressure to the stack through one of the pressure plates, an electromagnet having an armature member disposed to control the pressure applied in response to the energization of the electromagnet, a casing for the stack and associated spring and armature members for housing them, the casing having a diaphragm disposed for holding the other pressure plate, the casing having sealed joints to render the casing leakproof, a thermally conducting insulating medium disposed within the casing to envelop the stack and associated spring and armature members, and means comprising a member disposed in threaded engagement with the casing, the member also being in threaded engagement with the diaphragm thereby to effect a predetermined movement of the diaphragm to adjust the setting of the other pressure plate within the sealed casing as the member is turned relative to the casing.

2. In a sealed regulator, in combination, a stack of disks of resistance material, a pressure plate at each end of the stack of disks, a spring member disposed to apply pressure to the stack through one of the pressure plates, an electromagnet having an armature member disposed to control the pressure applied in response to the energization of the electromagnet, a casing for the stack and associated spring and armature members for housing them, the casing having a diaphragm disposed for holding the other pressure plate, the casing having sealed joints to render the casing leakproof, a thermally conducting insulating medium disposed within the casing to envelop the stack and associated spring and armature members, a threaded receiver carried by the diaphragm, an end cap carried by the casing disposed over a face of the diaphragm for movement relative thereto, and a threaded plug carried by the end cap disposed in threaded engagement with the receiver to effect an adjustment in the position of the diaphragm and the setting of the other pressure plate within the sealed casing when the end cap is moved.

3. In a sealed regulator, in combination, a stack of disks of resistance material, a pressure plate at each end of the stack of disks, a spring member disposed to apply pressure to the stack through one of the pressure plates, an electromagnet having an armature member disposed to control the pressure applied in response to the energization of the electromagnet, a casing for

the stack and associated spring and armature members for housing them, the casing having a diaphragm disposed for holding the other pressure plate, the casing having sealed joints to render the casing leakproof, a thermally conducting insulating medium disposed within the casing to envelop the stack and associated spring and armature members, a threaded receiver carried by the diaphragm, an end cap carried in threaded engagement by the casing disposed for movement relative to the diaphragm, and a

threaded plug carried by the end cap disposed in threaded engagement with the receiver to effect an adjustment in the position of the diaphragm and the setting of the other pressure plate within the sealed casing when the end cap is moved, the pitch of the threads of the end cap and the plug being predetermined to control the fineness of adjustment of the position of the diaphragm when the end cap is moved.

10

HASCUM O. AUSTIN.
